UNITED STATES PATENT OFFICE

2,435,365

DRAGGING EQUIPMENT DETECTOR

Ernest K. Post, Collingswood, N. J.

Application June 15, 1944, Serial No. 540,367

18 Claims. (Cl. 246—169)

1

My invention relates to a detector arm and a mount therefor adapted to be included within a signalling circuit for the detection of dragging brake beams, etc., hanging beneath a train.

In U. S. Patent No. 2,063,336 to Welles M. Post, a protective system for railways is illustrated in which detector elements appear. The present invention is directed to novel and effective detector arms and mounts therefor which are capable of use for the same purpose as those shown in the said patent.

One purpose of the invention is to reduce vibration in the detector.

A further purpose is to support detector arms from approximately the middle parts of the arms.

A further purpose is to stiffen the engaging face of a detector arm.

A further purpose is to mount a detector arm upon electrical conductors clamped between the bracket and the arm.

A further purpose is to mount a detector arm by grooved legs from a grooved bracket using the electric connecting wires for the circuit to form the actual engaging mechanical as well as electrical contact between the brackets and the arm.

A further purpose is to adapt a detector arm to use with standard ties as distinguished from the current practice which requires special lengths of tie.

A further purpose is to cast detector arms in channel form and to stiffen the arms by webs extending across the channels.

I have preferred to illustrate my invention by one form only, selecting a form which is practical, efficient, and inexpensive but which has been selected primarily because it illustrates the invention to excellent advantage.

Figure 1 is a top plan view showing my invention applied in standard railway practice.

Figure 2 is a transverse section of Figure 1 upon line 2—2, showing the features of the invention in front elevation.

Figure 3 is a right end elevation of the structure seen in Figure 1, showing the rail in side elevation.

Figure 4 is a fragmentary enlarged front elevation.

Figure 5 is a section taken upon line 5—5 of Figure 4.

Figure 6 is a section upon line 6—6, being largely a top plan view of the clamps by which the arm is mounted.

Figure 7 is a perspective view of a mounting bracket seen in the other figure.

2

In the drawings similar numerals indicate like parts.

My invention is adapted to be mounted upon standard equipment comprising standard length ties 11, rails 12, of different heights, for which the mount is adjustable, and tie plates 13.

The detector arms 14 comprise upper engaging bars 15 having bends 16, 16 connecting with reversed "return" sections 17, 18 and terminating in legs 19. The detector arms are mounted, one outside of each rail and preferably three between the rails. With the normal length of arm the entire space between the rails is protected adequately by three arms.

With present equipment, the center of the track has relatively received less protection than the parts adjacent the inside of the rails, with the result that it has been customary to use a wedge shaped ramp 20 to guide dragging equipment toward the rails. The ramp has a low apex 21 toward the traffic and progressively higher diverging sides 22. Such a ramp may be used with my present construction, and is quite desirable if the middle detector arm be not used, but there is less reason for it when a middle arm is used than there had been in the prior constructions.

The arms shown are connected in series and within the signalling circuit between conduit inlets and outlets 23, 24 by conductors 25, 26, 27, 28, 29 and 30 so that the signalling current passes from the conductor in one conduit through the successive conductors and intervening arms to the conductor in the other conduit.

In order to avoid large, solid masses of metal which would be particularly objectionable when broken because if they fell under the wheels they might cause derailments, substantially the entire length of the detector is of channelled form. The forward bar is channelled at 31 downwardly, and in the return sections the opening of the channel 31 is directed upwardly. The channels in the legs open at 31' rearwardly. It is desirable to stiffen these channels against stresses parallel to the direction of motion of traffic. In order to secure additional stiffening and additional resistance to stresses whether they be compressive or tensile, the sides of the channel are therefore connected at intervals by webs 32.

The arms are carried by brackets 33 having upright faces 34 engaging the sides of the ties and generally horizontal flange faces 35 resting on the tops of the ties. The brackets are held to the ties by bolts 36, washers and nuts 37.

The upright faces 31 of the brackets away from the ties are transversely grooved at 38 to receive

two lengths of wire 39, 40, and the interior rear faces of the legs or standards are correspondingly transversely grooved at 41 to a spacing corresponding with the spacing of the grooves of the brackets, but over a much larger upright area, whereby the legs can be adjusted to variant heights and at each of the variations in height, two of the grooves of the brackets will correspond in position with the two grooves in the brackets.

Each of the grooves in the brackets and legs or standards is a trifle less in depth than half the thickness of the wire. The legs are grooved at intermediate positions, so that additional adjustment positions are available, the intermediate positions being spaced, one from the next by the same spacing as that between bracket grooves.

Clamps 42 span the standards and are tightened to clamp the legs or standards and brackets together about the wires by suitable bolts 43 and nuts 44.

The wires 39 and 40 may be wholly separate wires against which the legs are clamped so that they physically space the legs from the brackets and cooperate in the mechanical positioning of the legs or, with the same mechanical effect, they may represent a loop as shown. In either case one of them will be a conductor wire in the series connection of the several arm units across from one side of the track to the other and this wire therefore will engage the walls of the leg groove and thus afford electrical contact with its leg.

If the loop form be used there is the additional electrical contact with the leg represented by the engagement of the walls of the other leg groove with the terminal end of the loop. There is, therefore, an advantage in the use of the loop everywhere except adjacent to the conduits. Because of a common practice of terminating the conduit connection in two wires which do not form a loop, two separate wires will most conveniently be used adjacent to the conduits.

As thus described, the units represented by the several arms and their supporting legs may be placed at any points along the lengths of the ties where the brackets can be placed and where there is no interference of one arm with the position of another.

The connecting wires ordinarily are stranded wires which may be sweated so as to give more solid conductor terminals for clamping purposes than would be the case if the relatively more loose independent stranded wires be used without such sweating.

It will be evident that the several parts of the arm unit are greatly stiffened by the transverse webbing and that the webs can be placed at relatively long spacing as in the engaging bars or at short spacing as in the legs, as may be desired.

It will be evident that the adjustment of the height of the engaging bars may be effected quickly throughout a wide range and without the use of other tools than the wrench by which the clamping bolts are tightened.

It will be evident that the shortened distance between the supports and the bends in the arms, as compared with the longer distance in the structure of the Post patent above, greatly reduces the objectional effects of such vibration as is inevitable in view of the connection of the arms with the tie.

Having thus described my invention, what I claim as new and desire to secure by Letters Patent is:

1. In a detector for dragging railway equip-

ment, a frangible front engagement bar, converging supporting bars connected to the ends of the engagement bar, legs for the supporting bars, a pair of electric wires extending transversely of the legs, brackets for supporting the wires and legs, and clamping means for forcing the legs against the wires and the wires against the brackets.

2. In a detector for dragging equipment on a railway track, an upper front frangible engagement bar channeled downwardly, converging bars connected at the ends of the front bar and channeled upwardly and legs for the supporting bars, channeled at right angles to the channeling of the other bars and webs across the channels of the bars and legs, the legs being grooved at intervals transversely with the bottoms of the grooves toward the backs of the channels.

3. In a detector for dragging equipment, a bracket having grooves in an upright face, an engaging arm, a leg supporting the arm having grooves in one face corresponding in general position with the grooves in the bracket, the bracket and arm as a unit being frangible, wires fitting partly into each of the grooves, a clamp and means for tightening the clamp, pressing the leg toward the bracket and clamping the wires between the two.

4. In a detector for dragging equipment, a bracket having grooves in an upright face, an engaging arm, a leg supporting the arm having grooves in one face corresponding in general position with the grooves in the bracket, the arm and leg units being frangible, wires fitting partly into each of the grooves, a clamp and means for tightening the clamp, pressing the leg toward the bracket and clamping the wires between the two, one of the wires connecting with corresponding bracket and leg members of another arm.

5. A plurality of arms spaced across a track, pairs of legs acting as supports for the arms and with which the arms are electrically in series, the arm and leg units being frangible, electric conductors joining adjacent legs of adjoining arms, so that the arms are in series, brackets supporting the several legs, each leg and the corresponding supporting bracket being grooved to admit an electrical conductor and clamping means for tightening each leg and its bracket against opposite sides of one of the conductors.

6. A detector for railway use having at the upper end an engagement bar reversely turned at its ends, each turned towards the other, legs by which the bar is mounted, the length of the detector and legs being channeled, the arm and leg units being frangible, and webs across from side to side of the channel at intervals more frequent in the legs than in the arm portions of the detector.

7. A detector arm for protection against dragging equipment comprising a pair of channeled legs having webs across from side to side of the channel and grooved at the back of the legs at regular intervals, diverging arm portions connecting with the tops of the legs and reversely turned and united to form an upper contact arm, the diverging portions and the connecting member having webs across from side to side, and the arm and leg units being frangible.

8. A detector arm for protection against dragging equipment comprising a pair of channeled legs having webs across from side to side of the channel and grooved at the back of the legs at regular intervals, diverging arm portions connecting with the tops of the legs and reversely turned

and united to form an upper contact arm, the diverging portions and the contact arm having webs across from side to side in combination with a bracket grooved on the facing side and wires resting in two grooves and a clamp and bolts forcing the legs against the wires and the wires against the brackets, the wires and bolts forming the only connection between the legs and the bracket, and the arm and leg units being frangible.

9. In a detector for dragging equipment, an engaging bar transversely turned and extending from both sides toward the middle, legs for the bar having transverse grooves uniformly spaced across the lower end, the bar and leg unit being frangible, a bracket having grooves across its upper end, electric wires filling the two grooves in the brackets and in the legs and spacing the bodies of the legs from the bodies of the brackets, means for fastening the brackets to ties, clamps engaging the opposite sides of the legs from the grooves and bolts holding the clamps to the brackets and tightening the legs against the wires.

10. In a detector for dragging equipment, legs channelled and having stiffening webs across their channels, grooved transversely back of their channels at uniform intervals, diverging upwardly channelled sections at the upper ends of the legs and a transverse, downwardly channelled bar connecting with the diverging sections and having webs across the channels, the bar and leg units being frangible, brackets adapted to support the legs, grooved transversely at spaced points, wires of which one is electrically conducting, entering corresponding grooves in the legs and in the brackets, clamps spanning the legs, bolts holding the clamps and brackets together, nuts for the bolts adapted to tighten the clamps against the fronts of the legs and to tighten the grooved portions of the legs against the wires and the wires against the brackets, and means for holding the brackets.

11. In a detector for dragging equipment, a transverse channelled upper engagement bar, oppositely directed channelled lower bars connected with the upper bar and extending towards each other, downwardly turned channelled legs having at intervals across the channels stiffening webs and the legs being grooved at intervals, the bar and leg units being frangible, transversely grooved brackets for supporting the detector bar, wires, of which one is an electrical conductor, lying between the grooves of the legs and the grooves within the brackets, the wires spacing the bodies of the legs respectively from the bodies of the brackets, clamps for the legs, and bolts passing through the clamps and tightening the legs, wires and brackets, whereby the detector is mounted upon transverse sections of the wire.

12. In a detector for dragging equipment upon a railway track, a tie, a plurality of brackets mounted at intervals along the length of the tie, between the rails and also outside of the rails, each bracket being grooved upon an upright face at different heights along said face of the bracket, a plurality of detector arms, one arm to each two brackets, legs connecting opposite ends of each arm with the two brackets for that arm, the legs being grooved at a spacing corresponding with the spacing of the grooves in the brackets and the arm and leg units being frangible and electrical conductors joining one leg of one bracket with the other leg of another bracket, whereby the respective arms are electrically connected in series, the ends of the conductors fitting each,

partly within the groove of one bracket and partly within the groove of one leg, clamps, and means for tightening the clamps to press the legs against the wires and the wires against the brackets whereby electrical connection between the wires and the arms is established and the wires cooperate in mechanically supporting the legs.

13. A plurality of frangible arms spaced across a track, pairs of terminals as supports for the

10 arms and with which the arms are electrically in series, electrical conductors joining adjacent arms by joining adjacent legs of different arms through the terminals to bring the arms into series, brackets supporting the several terminals and

15 clamping means between the brackets and terminals engaging the electrical conductors to complete the circuit.

14. A detector for railway use, comprising electrically conducting frangible bars extending transversely with respect to the rails, bar terminals having parallel spaced grooves, a plurality of electrically conducting wires fitting the

20 grooves of the terminals and supplying the bars with electric current through the contours of the grooves, mechanical supports for the terminals

25 having grooves spaced in correspondence with those of the terminals, fitting the opposite sides of the electrically conducting wires from the sides which engage the terminals, and means for forcing

30 the terminals and the mechanical supports toward the wires to grip the wires and cause good contact between the wires and the walls of the terminal grooves.

15. A frangible bar intended to form part of an

35 electric circuit to protect against dragging equipment, having terminals which contain parallel grooves, mechanical supports therefor having parallel grooves, a plurality of electric conductors adapted to supply electric current to and from

40 the frangible bar and clamping means forcing the supports and terminals toward each other to grip the electric conductors on opposite sides of the wires and at the same time through the wires mechanically to support the frangible bar.

16. An arm for protection of a track against

dragging equipment, a pair of legs supporting the arm, the assemblage of the arm with the legs being frangible, brackets supporting the legs, electrical conductors connected with the legs and clamping means for holding the legs and the brackets in engagement against the conductors whereby electrical connection to the legs and mechanical support between the brackets and the legs are secured by reason of the clamping action.

17. A plurality of frangible arms and legs therefor adapted to cover the space between rails in a railway track and including a transverse arm at the center of the track, a plurality of brackets

50 therefor, two for each arm, the arm and leg equipment being frangible, and the brackets being adapted to be clamped toward the legs, electrical conductors joining the brackets and the legs and clamping means holding the brackets and supports against the electrical means on opposite sides thereof.

18. In a detector for dragging equipment upon a railway track, a tie, a plurality of brackets mounted at intervals along the length of the tie,

70 between the rails and also outside of the rails, each bracket being grooved upon an upright face at different distances along said face of the bracket, a plurality of frangible detector arms, one arm to each two brackets, grooved connections between the ends of the arms and the

brackets and electrical conductors fitting, each partly within the groove of a bracket and partly within the groove of a connection and means for tightening the connections against the wires and the wires against the brackets, whereby electrical connection between the wires and the arms is established and the wires cooperate mechanically in supporting the brackets.
